FASTENING AND SHOES CONTAINING THE
FASTENING

Richard C. Marcy, Marblehead, Mass., assignor to
United Shoe Machinery Corporation, Flemington, N. J., a corporation of New Jersey

Application September 4, 1941, Serial No. 409,470

13 Claims. (Cl. 36—19)

This invention relates to fastenings and to shoes in which the fastenings may be used and it is illustrated herein with reference to single shank fastenings particularly adapted for use in securing outsoles to McKay shoes.

In attaching outsoles to shoes of the type referred to the outsole is laid on the lasted shoe bottom and is temporarily secured in position thereon to permit the last to be pulled out of the shoe and through-and-through stitches to be inserted through the outsole, the upper and the insole. Although various fastening means have been employed heretofore to hold the sole temporarily on the shoe bottom, the usual practice is to use staples which are normally inserted in the stitch receiving channel of the outsole, inwardly of the groove in which the sole attaching stitches are to be located. However, since the groove for the stitches is usually located near the inner extremity of the channel, the staples are necessarily positioned relatively close to the stitches.

If the staples are inserted so that their bar portions are located parallel to the edge face of the outsole, which will also be parallel to the row of sole attaching stitches when the latter are inserted, no trouble will ordinarily result from using staples in laying the outsole. However, if the staples should become turned or twisted from this parallel position while being inserted, as often happens, they are likely to extend into the path or plane in which the sole attaching stitches are to be located and therefore will be in a position to be struck by the needle of the sewing machine, in which case the needle may be damaged or even broken. Moreover, even though the bar portions of the staples are located substantially parallel to the path or line of the stitches, the legs of the staples often become clinched in diverse directions which sometimes causes one or the other of the legs to extend into or cross the path of the stitches and thus be in a position to be struck by the sewing needle and cause the latter to break.

Objects of the present invention are to provide an improved fastening which is particularly adapted to eliminate the above difficulties in work of the type referred to, and to provide an improved shoe having its outsole attached to the shoe by means of such fastenings.

To these ends and in accordance with one of its features, the invention provides, as a new article of manufacture, an improved fastening comprising a straight shank portion having its opposite end portions provided with sets of legs, each

set preferably comprising a pair, and the legs of one set being deflected laterally of the shank portion of the fastening within planes defined by opposite sides of said shank portion to provide a driving head on the fastening. As herein illustrated, the fastening may be formed by severing it from a straight length of rectangular wire by inclined cutting knives arranged to cross each other at predetermined angles and having means thereon which act during the cutting operation to deflect the upper pair of legs laterally in opposite directions but within parallel planes defined by two opposite surfaces of the shank portion, for example, the inner and outer sides thereof, to form the driving head. The knives are inclined in planes normal to the planes of said opposite sides of the shank portion of the fastening and at angles which produce correspondingly inclined or beveled surfaces on the legs of each pair, these beveled surfaces extending in opposite directions to each other in planes normal to the inner and outer sides of the fastening and at inclinations or angles which extend the full length of the legs and cause them to taper throughout their lengths while also producing chisel points on the ends of the legs. When the fastening is driven the bevels on the deflected legs at the driving end of the fastening cause these legs to become further bent or deflected so that they become clinched against the upper surface of the work piece into which the fastening is driven. The bevels on the opposite or lower pair of legs will cause these legs, when they engage clinching means such as a metal plate or anvil, to be bent or deflected in opposite directions laterally of the shank portion of the fastening but within the planes of the front and rear sides of said shank portion until these lower legs become clinched against the lower surface of the work piece.

The present fastening, therefore, provides means which, as herein illustrated, can be advantageously used in the type of work referred to for holding the outsole on the bottom of the shoe until the sole attaching stitches are inserted without danger of breaking the needle because, as indicated above, the fastening has only a single shank portion which is inserted substantially perpendicularly to the surface of the sole, and the legs on the opposite ends of the fastening are arranged to be deflected and clinched so that they will lie within the parallel planes of the front and rear sides of said shank portion so that, as illustrated, the clinched legs will

always be located parallel to the path or plane of the stitches in the stitch receiving channel.

In accordance with another feature, the invention provides an improved shoe consisting of an insole, an upper, and an outsole, and a row of separate fastenings securing the outsole to the insole and upper, each of these fastenings comprising a straight shank portion passing through the outsole, upper and insole and having its opposite ends provided with sets or pairs of legs which are clinched respectively against the insole and the outsole, and the legs of each pair being deflected laterally in opposite directions within planes defined by opposite sides of the shank portion of the fastening and extending parallel to the edge face of the outsole. As herein illustrated, the outsole may be attached to the shoe by the fastenings alone or, if desired, the fastenings may be used merely to hold the outsole in position until the sole attaching stitches are inserted. In the latter case, as pointed out above, the fastenings will not extend into the path or plane of the sole attaching stitches and, accordingly, there will be no danger of breaking the needle of the sewing machine when the stitches are inserted.

With the above and other objects and features in view, the invention will now be described in detail in connection with the accompanying drawing and will thereafter be pointed out in the claims.

In the drawing,

Fig. 1 is a perspective view of the new fastening after it has been severed from a length of wire;

Fig. 2 is a front elevation of the fastening being severed from the wire by inclined knives;

Fig. 3 is a fragmentary view in perspective and cross section showing one side of a McKay shoe the outsole of which has been secured in position by the present fastenings;

Fig. 4 is a perspective sectional view similar to Fig. 3 showing the outsole permanently attached to the shoe by through-and-through stitches;

Fig. 5 is a view similar to Fig. 3 showing an outsole being attached to a shoe by the present fastenings alone, the lower end of a driver being shown driving one of the fastenings;

Fig. 6 is a view similar to Fig. 4 showing the outsole permanently attached to the shoe by the fastenings;

Fig. 7 is a longitudinal section on an enlarged scale taken on the line VII—VII of Fig. 5; and

Fig. 8 is a cross section of the driver taken on the line VIII—VIII of Fig. 7.

The improved fastening is illustrated in detail in Figs. 1 and 2 and, as shown therein, comprises a straight shank or body portion 10 substantially rectangular in cross section and formed by cutting the fastening from a straight length of wire 12 which may be carried by a reel or other suitable means. The shank portion 10 of the fastening has its opposite end portions provided with sets of legs comprising a pair of legs 14 located at the lower end of the fastening and a pair of legs 16 located at its upper end.

As illustrated in Fig. 2, the fastenings may be severed from the length of wire 12 by a pair of inclined cutting knives 18 arranged to cross each other at opposite angles and in planes normal to the plane of the shank portion of the fastening, the inclinations of the two knives corresponding to inclinations or bevels desired on opposite sides of the legs of each pair to cause the legs to taper throughout their lengths and to have chisel

points formed on their outer ends. The knives 18 are provided at their lower ends with cutting edges formed by the upper sides 19 thereof meeting inclined lower surfaces 20 which are inclined 5 at such angles to the upper surfaces 19 that, when the knives are severing a fastening from the wire 12, the upper pair of legs 16, which the knives form as they sever the fastening, will be engaged by these inclined surfaces 20 and will be initially 10 deflected or bent in opposite directions to each other laterally of the shank portion of the fastening but within the planes of the front and rear sides of said shank portion, as best shown in Figs. 1 and 2, thereby providing a driving head 15 on the fastening.

As the knives sever the fastening 10 from the length of wire, they simultaneously form the lower pair of legs 14 of the next fastening so that, upon each operation of the knives, a completed fastening is cut from the wire with its lower pair of legs 14 beveled throughout their 20 lengths at opposite angles to each other to form chisel points and with its upper pair of legs 16 likewise beveled throughout their lengths at opposite angles to form points thereon but with the upper pair being also deflected laterally in opposite directions of the shank portion of the fastening so that they lie within planes defined by the front and rear sides thereof to provide the driving head. The knives 18 may be operated in any usual or convenient manner as, for example, in guideways by rack and pinion arrangements or by cam operated levers actuated from any usual source of power.

As illustrated in Fig. 1, the shank portion 10 of the fastening is about twice as thick in cross section as it is wide to permit the pairs of legs on its opposite ends to be formed with the legs of each pair located in side-by-side relation to each other. As herein illustrated, the surface 22 constitutes the front side of the fastening and the surface opposite the surface 22 (not shown) constitutes its rear or inner side. These front and rear surfaces of the rectangular fastening are parallel to each other and have been regarded herein as determining the plane or planes of the shank portion of the fastening within which the legs are clinched so that, when the legs 14 and 16 are defined in the specification or claims as being within or parallel to, the planes defined by opposite sides of said shank portion, the legs are considered to lie in positions within the planes of these front and rear surfaces of the fastening or, to state it in another way, to lie within the space defined by the planes of these surfaces and preferably parallel to such planes.

As pointed out above, one important use for which the present fastening is particularly adapted is that of securing the outsole of a McKay shoe in the position in which it has been laid on the shoe bottom until after the outsole has been permanently attached to the shoe by the usual through-and-through stitches. As illustrated in Fig. 3, an outsole 24, provided with a stitch receiving channel 26 and a channel flap 28, is laid on the bottom of a shoe comprising an upper 30 and an insole 32 which have been assembled on a last 34 provided with a metal bottom plate 36, the upper having been secured in overlasted relation to the insole in any usual manner as, for example, by cement or staples. After the outsole 24 has been laid on the shoe bottom, the fastenings 10 are driven substantially perpendicularly through the outsole, upper and insole 70 to hold the outsole temporarily in position on the

shoe bottom. As illustrated in Figs. 3 and 4, the fastenings 10 are located adjacent to the inner edge of the stitch receiving channel 26 and inwardly of the usual groove 38 in which the sole attaching stitches are located, the lower legs 14 of the fastenings being clinched against the inner surface of the insole by the metal plate 36 on the last bottom. The laterally deflected upper legs 16 of the fastening are likewise clinched by the driver against the surface of the outsole formed by the channel 26. As illustrated in Fig. 7, the pairs of legs 14 and 16 are deflected laterally and clinched during the driving operation in such a manner that they lie within planes defined by opposite sides of the shank portion 10 of the fastening or, in other words, so that they are located within and parallel to the planes of the front and rear surfaces of the fastening. Moreover, the shank portion of the fastening has been so located in the outsole that its front surface 22 and consequently the clinched legs are all parallel to the edge face of the outsole, which is indicated in Fig. 3 by the reference numeral 40.

After a sufficient number of fastenings 10 have been inserted in the shoe to hold the outsole 24 temporarily on the shoe bottom, the last 34 may be removed from the shoe, as shown in Fig. 4, and the outsole 24 permanently attached to the shoe bottom by through-and-through stitches 42 which will be located in the groove 38 of the stitch receiving channel 26 and will pass through the outsole, the overlasted upper 30 and the insole 32. After the sole attaching stitches 42 have been inserted, the channel flap 28 may be cemented and laid over the channel to cover the stitches and the driven fastenings 10. Since the clinched legs 14 and 16 are all located within the planes of the front and rear sides of the shank portion 10 of the fastening and are parallel to the edge face 40 of the outsole, they will not extend into the groove 38 in the stitch receiving channel and in the line or path of the sole attaching stitches 42. Consequently, the stitches 42 may be inserted without danger of the needle of the sewing machine striking one of the fastenings and damaging or breaking the needle. A machine which may advantageously be used for inserting the fastenings in the shoe is one of the general type disclosed in Letters Patent of the United States No. 786,190 granted March 28, 1905, on an application filed in the name of Louis A. Casgrain.

Fig. 7 illustrates, on an enlarged scale, the step of fastening an outsole to the upper and insole of a McKay type shoe by the use of the novel fastenings of this invention, the lower legs 14 of each fastening being deflected, in the driving operation, by the metal plate 51 on the bottom of the last toward the outer face of the outsole thus causing an effective clinching of the legs with their ends extending into the insole, the upper legs 16 being also clinched against the outer face of the outsole or the channel therein by a fastening inserting driver 44 which may be utilized in the machine for inserting the fastenings. The driver 44 preferably comprises an elongated metal bar of sufficient dimensions in cross section to engage the deflected legs 16 forming the driving head and drive the fastening and also to clinch the legs 16 in the manner illustrated in Fig. 7. The driver may, if desired, be shaped in cross section as shown in Fig. 8 so that it has a central portion 46 the full thickness of the fastening 10, and has oppositely extending

flanges or ribs 48 projecting from the central portion 46 for engaging the deflected legs 16 at the upper end of the fastening.

Since the present fastening, although comprising only a single shank portion, is provided at its opposite end portions with sets or pairs of legs which may be clinched to hold the fastening firmly in the work, the fastenings may, if desired, be utilized for permanently securing shoe parts together as, for example, for permanently attaching an outsole 50 to the bottom of a McKay shoe (Fig. 5) which, as illustrated, comprises an upper 52 assembled with an insole 54 on a last 56 having a metal bottom plate 57, the upper 52 being secured in overlasted relation to the insole by cement, staples, or other suitable means. When the fastenings alone are relied upon to hold the outsole permanently on the shoe bottom, they may be inserted somewhat closer together than in the previous shoe, as illustrated in Fig. 5, this figure also showing one of the fastenings being inserted by the driver 44. Moreover, since no sole attaching stitches are to be inserted, the fastenings may be located directly in the groove 58 which ordinarily receives the stitches, this groove, as stated, being formed near the inner edge of a stitch receiving channel 60 provided with a flap 62, which is the usual construction of outsoles for McKay shoes. After the fastenings 10 have been inserted around the outsole 50 and have attached it permanently to the bottom of the shoe 52, the channel flap 62 may be laid, as shown in Fig. 6, and cemented back in the channel to cover the fastenings, after which the last 56 may be removed from the shoe.

The shoe of Fig. 6 will have its outsole attached just as securely to the shoe bottom as the shoe of Fig. 4 because, as stated above, a sufficient number of fastenings 10 may be inserted 40 when no stitches are to be used to insure that the attachment of the outsole will be strong and permanent. Since each separate fastening is clinched at both ends the fastenings are firmly locked or anchored in the materials of the shoe 45 bottom and will not tend to work out during the wearing of the shoe. The fastenings, moreover, by reason of the manner in which they are clinched against the inner face of the insole 50 present no projections on the inside of the shoe such as might be perceptible in the wearing of the shoe.

When it is desired to utilize through-and-through stitches as well as the fastenings 10 for attaching outsoles to McKay shoes, the fastenings serve merely to hold the outsole in proper position on the shoe bottom until after the through-and-through stitches have been inserted. The fastenings are so located and clinched in the materials of the shoe bottom, however, that there is no danger of their extending into the path or line which the sole attaching stitches will follow and be in a position to cause the breaking of the needle during the stitching operation.

While the present fastening has been disclosed herein with reference to laying and attaching outsoles to McKay type shoes, it should be understood that the fastening is not limited to such uses but obviously has many other uses particularly in cases where a single shank fastening is desired which can be clinched at both ends in a manner which gives the fastening greatly increased holding power over fastenings which cannot be clinched in the manner indicated.

Having thus described my invention, what I

claim as new and desire to secure by Letters Patent of the United States is:

1. As a new article of manufacture, a fastening comprising a straight shank portion having two sides located opposite each other and having opposite end portions provided with sets of legs which taper throughout their lengths, the legs of one set being deflected laterally of said shank portion within planes defined by the opposite sides of said shank portion to provide a driving head on the fastening.

2. As a new article of manufacture, a metallic fastening comprising a straight shank portion which is rectangular in cross section and has its opposite end portions provided with pairs of legs, the legs of each pair tapering throughout their full lengths in opposite directions and the legs at one end portion being initially deflected in opposite directions laterally of said shank portion but within parallel planes defined by two opposite surfaces thereof to provide a driving head on the fastening.

3. As a new article of manufacture, a fastening comprising a straight shank portion having parallel front and rear surfaces and provided at its opposite end portions with pairs of legs, the legs of one pair being bent laterally of said shank portion within the planes defined by said front and rear surfaces to provide a driving head on the fastening, and the legs of the other pair being beveled at opposite angles to each other to provide points on said legs.

4. As a new article of manufacture, a fastening comprising a straight rectangular shank portion having pairs of legs formed on its opposite end portions, the legs of each pair being beveled at opposite angles to each other to provide tapered points on said legs, and the legs of one pair being bent in opposite directions laterally of said shank portion so that they lie within the space between the planes of two opposite sides of said shank portion to provide a head on the fastening by which it may be driven.

5. As a new article of manufacture, a fastening comprising a shank portion composed of a straight length of rectangular wire, said shank portion having pairs of legs provided at its opposite end portions, the legs of both pairs being beveled at opposite angles to each other to form chisel points thereon, and the legs of one pair being initially bent away from each other in opposite directions laterally of said shank portion to provide a driving head on the fastening, said legs being bent in directions parallel to the planes of the front and rear sides of the rectangular shank portion of the fastening.

6. As a new article of manufacture, a metallic fastening comprising a straight shank portion having parallel front and rear surfaces and having its opposite end portions provided with sets of legs, the legs of one set being deflected laterally of said shank portion but parallel to the planes of the front and rear surfaces thereof to provide a driving head on the fastening, and the legs of the other set being beveled at opposite angles to one another in planes normal to the planes of said surfaces to form chisel points on said legs, the bevels on said legs causing them when driven against clinching means to be deflected laterally of the shank portion of the fastening but within the planes of said front and rear surfaces.

7. As a new article of manufacture, a fastening adapted to be driven comprising a straight shank portion of rectangular cross section having its

opposite end portions provided with pairs of legs, the legs of one pair being deflected laterally of said shank portion in opposite directions but within parallel planes defined by opposite sides of the shank portion of the fastening to provide a driving head thereon, and the legs of the other pair being beveled lengthwise at oppositely inclined angles in planes normal to said parallel planes to form oppositely tapered legs having chisel points thereon, the bevels on said legs being such that, when the fastening is driven into a work piece and against clinching means, the legs will be deflected in opposite directions laterally of the shank portion of the fastening but within the parallel planes defined by said opposite sides of said shank portion.

8. As a new article of manufacture, a fastening comprising a shank portion composed of a straight length of rectangular wire having two parallel opposite sides and provided at its opposite end portions with pairs of legs, the legs of each pair being beveled at angles inclined oppositely to each other in planes normal to the planes of said opposite sides to provide legs which taper lengthwise and have chisel points thereon, and the legs of one pair being deflected in opposite directions laterally of said shank portion but lying within the planes defined by said opposite sides to provide a driving head on the fastening, the bevels on the deflected legs causing them to become clinched against one surface of a work piece within the planes of said opposite sides when the fastening is driven through the work piece and against clinching means supporting the same, and the bevels on the other pair of legs causing them to be deflected in opposite directions laterally of the fastening and to become clinched against the opposite surface of the work piece with the legs extending in positions which lie within the planes defined by said opposite sides of the shank portion of the fastening.

9. A shoe comprising an insole, an upper, and an outsole, and fastenings securing the outsole to the insole and upper, each of said fastenings comprising a straight shank portion passing through the outsole, upper and insole and having its opposite end portions provided with sets of legs which are tapered throughout their lengths and are clinched respectively against the insole and the outsole by being deflected laterally of the shank portion of the fastening within planes defined by opposite sides of said shank portion.

10. A shoe comprising an insole, an upper, and an outsole, and a row of fastenings extending around the margin of the outsole and securing it to the insole and upper, each of said fastenings comprising a straight shank portion passing through the outsole, upper and insole with the outer side of said shank portion parallel to the edge face of the outsole, said fastening being provided at its opposite end portions with pairs of legs, the legs of each pair being deflected in opposite directions laterally of said shank portion but within planes parallel to the plane of said outer side until the legs are clinched respectively against the inner surface of the insole and an outer surface on the outsole, with the clinched portions of said legs lying parallel to the edge face of the outsole.

11. A shoe comprising an insole, an upper, and an outsole, and a row of fastenings securing the outsole to the insole and upper, each of said fastenings comprising a straight shank portion

having inner and outer sides passing through the outsole, upper and insole and having its opposite end portions provided with pairs of legs which are beveled to provide chisel points on said legs, the bevels on the legs of each pair extending at opposite angles to each other in planes normal to the plane of the outer side of the fastening, and the legs of each pair being deflected in opposite directions laterally of the shank portion of the fastening but in positions lying within the planes of said inner and outer sides and being clinched respectively against the insole and outsole, the shank portions of said fastenings being located so that the clinched portions of the legs are parallel to the edge face of the outsole.

12. A shoe comprising an insole, an upper, and an outsole, a row of through-and-through stitches located parallel to the edge face of the outsole and securing the outsole to the insole and upper, and a row of fastenings adjacent to the stitches and passing through the outsole, upper and insole, each of said fastenings comprising a straight rectangular shank portion having its inner and outer sides parallel to the edge face of the outsole and to each other and having its opposite end portions provided with sets of legs which are clinched respectively against the insole and outsole, and the legs of each set being clinched by being deflected laterally of the shank portion of the fastening but in positions lying within and parallel to the planes defined by said inner and outer sides so

that when clinched said legs are parallel to the row of stitches and do not extend into the path of said stitches.

13. A shoe comprising an insole, an upper, and an outsole, a row of through-and-through stitches extending around the margin of the outsole parallel to its edge face and securing said outsole to the insole and upper, and a row of separate fastenings extending around the outsole parallel to the row of stitches and closely adjacent thereto, said fastenings passing through the outsole, upper and insole, each of said fastenings comprising a shank portion composed of a straight length of wire having its opposite sides parallel and its opposite end portions provided with pairs of legs which are clinched respectively against the inner surface of the insole and an outer surface on the outsole, the legs of each pair being beveled at opposite angles to each other in planes normal to planes defined by the inner and outer sides of the shank portion of the fastening to provide chisel points on said legs, said legs being deflected laterally of said shank portion in opposite directions when clinched but remaining within the planes defined by the inner and outer sides of said shank portion, and the shank portions of all of said fastenings being located in the outsole so that the clinched legs are parallel to the edge face of the outsole and do not extend into the path of said stitches.

RICHARD C. MARCY.
